UNITED STATES PATENT OFFICE

CLIFFORD J. LARKIN, OF EVERETT, MASSACHUSETTS.

RIDING-BREECHES.

967,023.

Specification of Letters Patent.

Patented Aug. 9, 1910.

Application filed October 8, 1909. Serial No. 521,731.

To all whom it may concern:

Be it known that I, CLIFFORD J. LARKIN, a citizen of the United States, residing at Everett, county of Middlesex, and State of 5 Massachusetts, have invented an Improvement in Riding-Breeches, of which the following description, in connection with the accompanying drawing, is a specification, like characters on the drawing representing 10 like parts.

This invention relates to riding breeches and has for its object to provide a construction whereby a perfect fit under the knee can be readily obtained without the presence of 15 any objectionable fullness at this point.

One of the difficulties heretofore experienced in making riding breeches has been to obtain such a shape under the knee that there will not be any fullness in the material at 20 this point when the breeches are being worn in the saddle to cause wrinkles or puckers in the cloth, the presence of which are very apt to chafe and annoy the rider. The present practice is to obtain an approximation of 25 this desired shape by stretching the cloth comprising the rear section of the leg along the in-seam and at the same time shrinking the portion of the cloth that comes under the knee, this stretching and shrinking process 30 being done before the pieces of cloth comprising the breeches are seamed together. This method of shaping the breeches leg is not only laborious, thus adding greatly to the expense of making the breeches, but it 35 does not give the breeches a permanent shape which will be retained if they become wet or after they have been worn for a considerable length of time.

In making my present invention I have 40 aimed to overcome the disadvantages inherent in the prior methods of cutting and making riding breeches and to provide a novel means of taking up this objectionable fullness under the knee without shrinking or 45 stretching the goods, so that the breeches may be given a permanent shape that will not be lost after they have been worn for some time or even if they become wet. I accomplish this object by cutting and seam- 50 ing up the rear section of the leg in such a way that the length of the leg is reduced on a line extending from the crotch divergently from the inseam and passing under the knee without reducing the length of the inseam. 55 The preferred manner of securing this result is illustrated in the drawings and herein de-

scribed, and the novel features of the invention are pointed out in the appended claims.

Referring to the drawings wherein I have shown one embodiment of my invention, 60 Figure 1 is a rear view of a pair of riding breeches made in accordance with my invention; Fig. 2 shows the pattern by which the rear section of the leg is cut; Fig. 3 shows it after the dart which is formed therein has 65 been sewed up; Fig. 4 shows how the material of the breeches is taken up under the knee without altering the length of the inseam.

In cutting my improved breeches, the 70 pieces constituting the front of the legs are cut in the usual way, but those constituting the rear of the legs, or, as I will hereinafter term them, the rear leg sections, are cut in a novel manner so as to permit of securing 75 the result aimed at. In the preferred embodiment of my invention I cut the rear leg sections according to the pattern shown in Fig. 2 which has the outside seam edge 5 of usual shape extending from the top to the 80 bottom of the piece, the edge 6 extending from the top of the section to the point 7 which comes at the crotch of the breeches and which edge forms part of the rear seam 8 of the breeches, and the in-seam edge 4 85 extending from the point 7 to the point 15 near the lower end of the pattern. Said pattern is also cut with a dart or V 3 which extends from a point adjacent the lower end of the in-seam edge 4 upwardly into the 90 piece of goods toward approximately the center of the edge 5 to a point 10, and this dart is preferably cut of the special shape shown with the comparatively straight edge 11 on the side of the dart toward the lower 95 edge 12 of the section and with the curved or hollowed edge 13 on the opposite side, said curved edge terminating at a point 14 situated a slight distance in from the corner 15.

The shape of the curved edge 13 of the dart is such that the length of said edge between the points 10 and 14 is approximately the same as the length of the straight edge 11. After the section has been cut according to this shape, the dart is seamed up to form the seam 21, as shown in Figs. 1 and 3, by bringing the edges 11 and 13 together so that the dotted lines 16 and 17 will coincide and then stitching the two parts along these 110 two dotted lines. When this step has been accomplished, the piece has the appearance

shown in Fig. 3 and the edge portion 18 of the dart comes in line with and forms practically a continuation of the lower edge 12. During this process of forming the dart and 5 seaming it up, the total length of the inseam between the points 7 and 15 has not been decreased or increased but the length of the material along the dotted line *a* in Fig. 2 or the folded edge 30 in Figs. 1 and 10 4, has been materially shortened; in fact in riding breeches of the ordinary size this method of forming the dart and seaming it up results in shortening the material between two and three inches along the dotted line *a*. This dotted line indicates the 15 portion of the breeches which passes down the inside of the leg under the knee and the portion of the breeches at the dart is that portion which comes directly under the 20 knee. By thus forming the dart and sewing it up as above described a shape is given to the underside of the breeches by which all fullness under the knee is eliminated so that when the breeches are worn, they will fit 25 the leg closely at this point and no wrinkles or puckers will appear which are liable to chafe and make discomfort for the rider. The important point of the invention is to 30 secure this shortening of the material along approximately the dotted line *a* without shortening the length of the inseam, and I have described above the preferred manner of accomplishing this. By means of my improvement this desired shape is given to the 35 breeches without changing the length of the inseam edge 4 and without any stretching or shrinking of the goods. Consequently, the process of making my improved breeches is no more elaborate than the process of 40 making any trousers, for it simply consists in cutting the pieces to the right shape and

then seaming them up, and this may be done without even going through the preliminary step of basting. The shape which I produce is permanent and will not be affected 45 by moisture and it can be readily secured even though the breeches are made of a very inflexible material, such, for instance, as khaki.

Riding breeches can be made in accordance 50 with my invention at much less expense because all the laborious process of stretching and shrinking is done away with.

Having fully described my invention, what I claim as new and desire to secure by 55 Letters Patent is:—

1. Riding breeches having the material of the rear leg section formed with a dart which extends from a point adjacent the lower end of the inseam toward the outside 60 seam in an upwardly inclined direction so as to pass under the knee, and which is of such a shape as to reduce the length of the leg on a line extending from the crotch divergently from the inseam and passing under the knee without reducing the length of 65 the inseam.

2. A rear leg section for riding breeches formed with a dart near the lower end of the inseam, which dart extends upwardly 70 into the section toward the outside edge seam and has one straight edge and a curved edge of substantially the same length as the straight edge but which terminates at a point inside of the inseam edge.

In testimony whereof, I have signed my name to this specification, in the presence of two subscribing witnesses.

CLIFFORD J. LARKIN.
